LUGENE R. DECKER, OF BROCTON, NEW YORK

BASKET

Application filed September 10, 1930. Serial No. 481,057.

This invention relates to baskets and particularly to that class of baskets generally used for packing and shipping fruit, vegetables and the like.

5 At the present time it is customary to pack such products at packing houses, the cartons or baskets being partially assembled before filling, and thereafter completely closed. The packed baskets are then 10 loaded on trucks or freight cars for transportation to markets or wholesale houses, many baskets being superposed one on another, to form high stacks, which are jammed together laterally, in order to utilize 15 the car space to best advantage. After reaching their destination but before delivery to purchasers it is sometimes necessary, due to Federal or State regulations, to open the baskets for inspection, and subsequently close 20 them for delivery.

The present invention contemplates a basket particularly adapted for such use, and briefly stated, comprises a main tubular body, which forms the sides of the basket, bottom 25 and cover members, and means associated with the body and the bottom and cover members by which these parts may be releasably held together. The tubular body member is preferably of tapering formation so that a 30 number of these parts may be telescoped for delivery to packing houses, while the cover and bottom members are flat and may be stacked in compact bundles for such delivery. The releasable securing means are fixed to the 35 tubular members at the time the latter are constructed, and the parts are so designed for cooperation with the securing means that after filling with fruit or vegetables, they may be locked together to form a closed container by relative movement of the parts, 40 without the use of nails or other securing means or the deformation of any of the parts.

The tubular member comprises a plurality of staves or stakes held together by hoops secured to their ends, and the flat cover members, coextensive with the hoops, directly abut the staves and hoops in assembled relationship so that when baskets are arranged in a freight car or other conveyance, the weight 45 of superposed baskets will be transmitted

from the top members, directly through the staves to the bottom members, and thence to the subjacent top flat member. Any stresses transmitted to baskets in one vertical stack from those in adjacent stacks, such as may be set up due to the inertia of the loaded fruit when the car starts or stops suddenly, will be absorbed by the hoops, which are strengthened to resist such lateral forces, and which are the only parts of adjacent baskets 55 60 which will contact.

The bottom members, being releasably securable to the body members, in the same manner as the top members, enable the packer to introduce the produce from the bottom 65 of the basket, while it is in inverted position and has the flat top cover attached, thus insuring that the top layer of fruit or vegetables, which is the first packed, will be uniform and level with the basket top. This 70 75 may be done without the likelihood of crushing the top layer of fruit, which is usually of the most choice fruit, as may easily occur in packing a basket of the type which opens only from the top.

The novel securing means requiring only relative movement of the parts for interlocking, enable the ready inspection of the fruit without damaging either the basket or the contained produce and may be accomplished 80 without the use of tools or fasteners. The even distribution of stresses and strains obtained by the utilization of the present invention permit of the use of a cheaper grade of wood, than is ordinarily used in baskets 85 of this general type, and this together with the simplicity of design, which eliminates intricate wood working and jointing in the construction of the baskets, materially lessens the cost of manufacture.

These and other objects and advantages will appear in the following description of a typical basket incorporating the principles of this invention, reference being made to the accompanying drawings, wherein:

Fig. 1 is a perspective view showing the basket with top and bottom members secured in their assembled position.

Fig. 2 is a vertical cross section taken through the center of the basket, the parts 100

being in the relative positions shown in Fig. 1.

Fig. 3 is an enlarged perspective view of a preferred form of fastening or securing device for releasably maintaining in closing positions the top and bottom cover members.

Fig. 4 is a perspective view showing the basket inverted and packed, the protective liner and bottom being removed.

10 Figs. 5 and 6 are fragmentary plan views showing cover members on the basket respectively in unlocked and locked positions.

Fig. 7 is a detail perspective view of a modified form of securing device.

15 Fig. 8 is a side elevation view of a modified basket construction.

As shown in Figs. 1 and 2 the basket or container includes a tapered tubular body portion 11, which comprises substantially 20 straight staves or stakes 12 secured together at their upper ends by and held between concentric inner and outer hoops 13 and 14, respectively, and secured at their lower ends by similar but smaller hoops 15 and 16, the 25 hoops being flush with the stave ends. Flat top and bottom members 17 and 18, respectively, coextensive with the hoops 14 and 16, are adapted to form the closure or cover members of the basket, being releasably secured to the body 11 by wire fastening hooks 20. The members 17 and 18 each comprise upper and lower pairs of substantially semi-circular strips 21 and 22, arranged at right angles, and the strips of each pair are flattened at 23, opposite their diametral edges, and secured together in spaced relation, thus providing notches 24 spaced at 90° about the peripheries of the cover members. The completed covers, due to the angular disposition of the component layers of strips are of considerable strength, but being laminated, the covers have sufficient resilience so that when loaded, as by one filled basket being superposed on another, they will spring into 40 abutting contact with, conforming to any irregularities in, the flush hoop edges and stave ends. Obviously, the strips may be arranged in other relationships to provide the notches at other angles if it is desired to do so.

45 50 The hooks 20 each comprise a single length of wire bent to generally U-shape, each of the legs of the U being formed to approximately S-shape, providing a cover-receiving channel 25 and a hoop clamping end 26. The 55 hooks or clips 20 are arranged about the upper and lower hoops, the ends 26 being passed through the stave members and clamped thereover at points spaced to correspond to the spacing of the notches 24 in the cover members, the clamping action consisting of bending the legs upwardly from the broken line to full line position shown in Fig. 3.

In Fig. 7 is depicted a modified fastening clip 20' which comprises a flat strip of metal 60 formed with a channel portion 30 for engage-

ment with a cover member, and a tongue 31 having apertures 32 for receiving nails or other fastening elements which secure the clip to the basket body 11. It is to be understood that a type of clamp means similar to that illustrated at 26 in Fig. 3 may be substituted for the means 31, 32, if desired.

It is contemplated that the tubular bodies 11 be completely assembled with the clamps 20 or 20' at the factory or shop and transported to packing houses in telescoped bundles, the tapered formation of the bodies permitting of this. The cover members are also built up to the form shown in Fig. 4 and may be shipped in compact bundles to the packing station. When a basket is to be filled with produce, the top cover 17 is first secured to the body, this operation being accomplished by placing the cover with notches 24 in registry with the clips 20, as depicted in Fig. 5, and rotating the cover relative to the body in either direction, as indicated by the arrows, to the position shown in Fig. 6, where the cover will engage in the channel 25, thereby locking the parts together. The basket is then inverted, as shown in Fig. 4 and a liner 35 of heavy paper is preferably placed therein, to prevent possible bruising of the produce during shipment, and the basket is packed in the usual manner. The first layer of fruit, since the basket is inverted, will be the top layer and this will be even, conforming to the flat surface of the cover, and will, when the basket is again opened, present a neat and pleasing appearance. Between layers of produce and over the last layer, other liners 35 are preferably placed, and the basket being filled, the bottom cover 18 is secured in place in the same manner as was the top 17. It will be apparent that while it is advantageous to pack the basket in inverted position, the operation may be reversed if desired, packing the basket from the top, after first securing in place the bottom 18.

110 Figure 8 illustrates a modified basket construction in which certain of the staves 12' are extended above the upper hoops 13 and 14 so that the upper cover member 17 will be spaced slightly from the upper hoops. With this form of basket it is preferred that the fastening clips 20 be secured through the hoops and the upwardly extended staves. As in the construction first described strains will be transmitted directly from the top cover to the bottom cover through the staves contacting with the covers, which in this modification are the staves 12'.

115 120 125 It will be understood that the basket may be opened for inspection and again closed, without in any way destroying or mutilating any part of the basket or its contents and that the basket may be repeatedly used. When loaded in a freight car or truck, the baskets may be superposed one on another and others side by side, without danger of bruising the prod-

- uce since vertical loads will be transmitted from the top cover members, which abut the stave ends, directly through the staves to the lower cover members, while horizontal forces 5 due to movement of the conveyance will be absorbed by the hoops, which by their association with the staves, are comparatively rigid, and which are additionally reinforced by the cover members. There is little likelihood of 10 the staves themselves being subjected to lateral forces since the hoops 14, being of larger diameter, will be the only portions of adjacent baskets to contact. If it is desired to seal the baskets for any reason, a very light nail 15 may be driven through the cover members into the hoops or staves, at one point as it is only necessary to prevent relative rotation of the covers and bodies, in order to prevent opening of the baskets. 20 It will further be understood that the specific article described may be modified in various details, and it is intended that the invention should be commensurate with the scope of the following claims. 25 What is claimed is:
1. In an article of the class described, a flat substantially circular cover having notches about its circumference, a body comprising a plurality of staves secured together by inner and outer hoops, and clip members having 30 portions extending through said staves and clamped about said hoops and portions for engaging said cover at the circumference thereof, said clip members being spaced relatively to said notches in said cover in such a manner that the cover may be rotated relatively to said body to bring said notches into alignment with said clips, whereby the cover 35 may be removed from the body. 40 2. In an article of the class described, a tubular body having inner and outer reinforcing hoops at both ends, flat cover members coextensive with, and for closing the ends of said body, said covers having notches 45 about the peripheries thereof, and clips for releasably retaining said covers for abutment with said tubular body and reinforcing hoops, said clips comprising portions adapted to overlie said cover members and portions passing through said body portion and clamped 50 about said reinforcing hoops, said covers having cut away portions whereby upon rotation of the covers said cut away portions may be aligned with said clips and the cover may be removed. 55 3. In an article of the class described, a body member having longitudinally disposed stave means, a reinforcing hoop about the open upper end of the body, a substantially flat cover member, portions of stave means being extended above the reinforcing hoop for abutment with the cover and for spacing it from the reinforcing hoop, and means secured to the extended portions of

the stave means for securing the cover to the body.

4. In a basket, a body member having substantially closed side walls and having a reinforcing hoop at the upper end of the side walls, portions of the side walls being extended above the reinforcing hoop, said extended portions being spaced about the periphery of the hoop, and a substantially flat cover member overlying and abutting the extended portions, whereby openings are provided between the hoop and cover member for viewing the contents of the basket, and whereby forces applied to the cover member may be distributed directly to the side walls 70 through the extended portions thereof. 75

5. In a basket, a body member having vertically disposed stave means, a reinforcing hoop about the upper end of the body, a flat closure member for the upper end of the body, portions of the stave means at spaced intervals about the periphery of the body being extended above the reinforcing hoop into abutment with the closure, said extended portions spacing the closure from the 80 reinforcing hoop and the space between the extended portions providing openings between the hoop and closure for viewing the upper contents of the basket, and means extending from the extended portions for releasably securing the closure member thereto. 85

6. In a basket, a body member having vertically disposed stave means, a reinforcing hoop about the upper end of the body, a closure for the upper end of the body, portions of the stave means at spaced intervals about the periphery of the body being extended above the reinforcing hoop into abutment with the closure, said extended portions spacing the closure from the reinforcing 90 hoop and providing openings through the basket between the hoop and closure, and means secured to the body member for releasably securing the closure in abutment with said extended portions. 95 100

7. In a basket, a body comprising a plurality of stave members secured together at their upper ends by a hoop member, a plurality of clips including means extending from each clip for securing it to one of said members, a flat substantially circular cover having notches about its periphery, said cover abutting the ends of said stave members, and said clips having portions engaging over said cover at the circumference thereof for retaining the cover in abutment with the ends of the stave members, said clips being spaced relatively to the notches in said cover in such manner that the cover may be rotated relatively to said body to bring said notches into alignment with the clips, whereupon the cover may be removed from the body. 115 120

8. In a basket, a body member having vertically disposed staves secured together ad-

jacent their upper ends by a hoop member; a cover comprising a pair of spaced substantially flat strips, having straight adjacent edges and having other edges circular,
5 a second pair of flat strips superposed upon said first mentioned strips and angularly related thereto, said second strips being similar to said first strips and angularly related thereto, the circular edges defining the substantially circular contour of the cover, and the space between the strips defining notches about the periphery of the cover; the ends of said staves abutting the under surface of the cover adjacent the periphery thereof, and clips secured to the body extending upwardly over the peripheral edges of the cover and thence inwardly over the upper surface of the cover adjacent the periphery thereof for retaining the
15 cover in abutment with the stave ends; said clips being so related to the notches of the cover that upon partial rotation of the cover they may be brought into registry with the notches for passing through the notches to effect removal of the cover.
